MACHINE FOR THE MANUFACTURE OF WIRE TACKS

Hans Stutzer, Kolin-Bickendorf, Wilhelm Wattler, Kolin-Zollstock, and Matthias Hermann, Kolin-Raderberg, Germany

Application July 10, 1950, Serial No. 172,866

Claims priority, application Germany July 25, 1949

6 Claims. (Cl. 10—49)

The machines hitherto used for the manufacture of wire tacks work relatively slowly. This arises both from their method of operation and their constructional layout.

As regards their method of operation the wire feed during the individual stages of reduction for shaping the shank is effected by the wire being seized afresh and fed forward both for the main feed step and also for each individual secondary feed step.

As regards constructional lay-out the known machines are provided with only a single control shaft. This carries various cams which, through lateral rises or swells and levers, actuate the die slide for upsetting the head, the knife slide, the two feed slides for the main feed of the wire, and for the secondary feed steps during reduction, and finally the reducing lever for the reducing dies in which if necessary the wire is at the same time held fixed during upsetting of the head.

The output of these machines is limited by the fact that the numerous parts have relatively large mass and in particular that the arrangement for the feeding of the wire, on account of its inertia and the exclusively positive engagement between the individual parts, is ill-adapted for carrying out the secondary feed steps of the wire for the second and further reductions since this feed arrangement has to be moved forward and backward at each separate feed step. The employment of a plurality of reductions and therefore short secondary feed steps of the wire cannot be avoided, because with only a single reduction the pressure would be higher and the pressing jaws wider than desirable, and in each case would have to be made equal to the exact length of the tack to be made. As a result the wire would be pressed out too long and too thin, particularly at the rear where the reduction of the shank is greatest. The pressed-out material could not, however, be used for making the next tack head, because the too long and too thin end would bend over and the head would be formed to one side on the shank. When a plurality of reduction steps is effected the pressed-out end is only very short and after each reduction is again thrust between the pressing jaws so that the head is pressed on the full wire diameter and is round and central. Further, in these known machines the upsetting of the head and the cutting off of the finished article, as already mentioned, is exclusively positively controlled, which with the generally long strokes of the parts of the mechanism affects the output capacity of the machine. Finally, the roller of the reducing lever runs on a lateral cam rise so that the roller is greatly limited in its diameter and the parts easily heat up. This also limits the output capacity of the known machines.

According to the invention the method of operation differs from that known by the feature that the wire stock is gripped once only for carrying out all its forward feed steps: that is to say, both for its main feed step and also all the secondary feed steps, and is fed forward with a divided movement without change of direction of movement of the wire gripping means and without release and re-gripping of the wire.

2

It will be obvious that the use of this method on the known machines and alteration of the known construction solely in this respect will make possible a substantial increase in output because the accelerations of mass, even with positive engagement of the parts transmitting motion, can be easily effected and only the single return stroke has to be carried out under the action of a spring.

But according to the invention the machine is also adapted in its construction on the one hand to the new method of operation and on the other in other respects; in particular the machine is constructed as a three-shaft machine, the side shafts being driven from the main shaft through equal ratio bevel wheels so that all three shafts rotate in unison. Such three-shaft machines are already known in the case of wire pin machines. But these, in contradistinction to wire tack machines, work without shank reduction so that the problems with which the invention deals do not arise in them.

The forward feed of the wire according to the invention is effected from one of these side shafts through a feed cam having an adjustable rise or swell for each feed step and always in a forward direction without release of the wire, through a single, light double arm lever, while the reducing lever is arranged at 90° to its usual position and now coacts with a cam disc having a plurality of radially inset and adjustable rises or swells, so that its roller can now be made of large diameter, and hot running due to further increase of pressure is avoided.

Even though the output of the machine is substantially increased by these arrangements, to increase it still further positive operation of the heading die slide and the cut-off slide for example through an eccentric (by which term I include a crank) and connecting rod is employed in conjunction with the three shafts.

Corresponding with the constructional features of the invention, the main shaft is in the form of a crank shaft, and carries means for receiving the drive, the connecting rod for the heading die slide and two toothed bevel wheels for transmitting rotation to the two side shafts, of which one carries the knife eccentric and the reducing cam with the adjustable rises or swells as well as a cam for the delivery device, while to the other are secured the other knife eccentric and the feed cam with its rises or swells for the main feed and after-feeds of the wire.

The machine must also have a pincer slide for the feed of the wire, which is provided with a gripper member which is retracted by a spring and thereby at the same time holds the feed-in lever against the feed cam.

Further, the gripper member positively moved longitudinally by the feed-in lever, may have a special form in that it has a piston-like extension which engages, and is longitudinally slidably in, a cylindrical holder. The stroke of the gripper may be limited by an adjusting screw projecting into the cylindrical holder and if it is made a substantially air-tight fit its movement may be damped by an air vent from the bore in the holder. In this way trouble free running of the machine is obtained.

The increase in output capacity of such a machine is so great that it amounts to about eighty per cent of the output hitherto obtained. For this reason the same machines can also be used to manufacture wire pins if the parts used for reduction are put out of action. Such conversion of a wire tack machine into a wire pin machine was not possible hitherto, because working with a tack machine was uneconomical. Through the increase in output this impediment disappears. The advantage of this possibility is that machine plant of a factory can be substantially reduced since production can be changed over as desired. It is thus immediately possible, in the absence of orders for wire tacks, to use the wire tack machines for increased production of wire pins and thus to reduce the machine plant in respect of wire pin ma-

chines, as well as to build machines for both purposes operating in accordance with the new method, and thus to effect substantial savings.

An example of wire tack machine in accordance with the present invention is illustrated in the accompanying drawings.

Fig. 1 is a plan view of the machine.

Fig. 2 is a detail of Fig. 1.

Fig. 3 is a face view of the feed cam.

Fig. 4 is a side view of Fig. 3.

Fig. 5 is a development of the lateral rises or swells of the feed cam of Fig. 3.

Fig. 6 is a side view of the reduction cam, and

Fig. 7 is an edge view of Fig. 6.

According to Fig. 1 the machine is provided with three shafts. The main shaft 10 carries at one end, for example a fixed pulley 11 and a loose pulley 12, as well as a hand wheel 13 for setting the machine. The side shafts 16 and 17 are driven through two pairs of bevel wheels 14 and 15. The two shafts carry eccentrics 18 and 19 by which the knife slides 22 and 23 are actuated through connecting rods 20 and 21. The main shaft 10 is provided with a crank 24, and through a connecting rod 25 operates the heading-die slide 26 for upsetting the head of the tack. On the shaft 16 is a reduction cam 27 with inset adjustable swells 28 and 29 having lug portions 50 and 51 for attachment to the cam by studs 52 and 53 (see Figs. 6 and 7) for effecting the various stages of reduction. On the shaft 17 is secured a cam disc 30 which is provided with the swells 31, 32, 33 and 34 (Figs. 3 to 5), and serves for the wire feed. Swells 31 and 32 are provided with slotted portions 54 and 55 to receive clamping studs 56 and 57 which threadedly engage the cam to permit lateral adjustment of the swells. The swells work upon a two armed lever 35 pivoted at 37, which bears against them with a roller 36. The roller 36 can be made greater in diameter than was possible hitherto because a change in the direction of the swells only occurs at one place, whereas elsewhere the swells always rise in the same direction. At this point also therefore, as previously pointed out with regard to the reduction cam, a decrease in heat development is achieved and the security of the machine is increased by this measure. The other end of the lever serves for longitudinally moving the gripper member 38 which is adapted for one-way engagement with wire stock (not shown) to be fed into the machine toward the left, as viewed in Figure 1, which has a piston-like extension 39 moving in a cylindrical bore 40 shown dotted in Fig. 2 in a corresponding holder member 48. The stroke of the feed mechanism 38 is limited by an adjusting screw 41 and damping of the movement in the cylindrical bore is effected by an air vent 42. The gripper member, as Fig. 1 shows, is pushed forward (toward the left) against a spring 43, which at the same time presses the double lever 35 against the swells of the feed cam 30. The adjusting screw 41, by limiting the return stroke of the gripper member 38, therefore serves to produce differences in the shaft length of the tack by changing the stroke, the swells 31, 32, being adjusted to suit. Greater changes in the main feed movement are effected by adjusting the swell 33 about a pivotal connection 46 by means of a screw 49 provided on the cam 30, or changing it for another of greater or less height. Use can be made of a set of calibrated swell pieces which simply need to be exchanged. The swells 31, 32, then have to be suited to the leading end 44 of the calibrated piece 33. The calibrated piece 33 has the same run-off part 45 for all rises. During its adjustment the calibrated piece 33 can be swung about its pivotal axis 46. In place of the adjusting screw 41 which serves as a stop for limiting the stroke of the gripper member 38, a corresponding abutment 47 can be provided on the feed cam 30, or some similar stop.

We claim:

1. Machine for the manufacture of wire tacks, comprising a main shaft and two side shafts at right angles to said main shaft, a heading die slide, an eccentric carried by said main shaft and a connecting rod coacting with said eccentric to actuate said heading die slide, a pair of knife slides, and means actuated by each of said side shafts for positively reciprocating said knife slides respectively, in combination therewith means for reducing the shank of a tack, a reducing cam on one of said side shafts for operating said shank reducing means several times during the production of a single tack, a gripper member for feeding the wire stock, a feed cam on the other of said side shafts, transmission means between said gripper member and said feed cam, said feed cam having a sequence of successively rising swells adapted through the intermediary of said transmission means to move said gripper member in the feeding direction in a sequence of steps asynchronous to the operation of said reducing means during the production of a single tack, and also having a run off portion following upon the sequence of successively rising swells to allow said gripper to return into its initial position.

2. Machine for the manufacture of wire tacks as set forth in claim 1, wherein the transmission means between the gripper member and the feed cam consists of a rocker lever one extremity of which engages the gripper member whereas its other extremity carries a roller maintained in contact with the working surface of the feed cam by a spring which constitutes the means for assisting the return of said gripper member into its initial position.

3. In a machine for the manufacture of wire tacks as set forth in claim 1, means for damping the movement of said gripper member comprising a piston-like extension on the gripper member, and a holding member having a cylindrical bore accommodating said piston-like extension to cushion the return movement of the gripper member, and means for limiting the return movement of the gripper member and thus determining the length of wire stock fed by said gripper member.

4. In a machine for the manufacture of wire tacks as set forth in claim 1, means for adjusting the height of the individual rising swells on the feed cam to determine each step of the progressive feed movements of the gripper under the action of the successively rising swells on the feed cam.

5. In a machine for the manufacture of wire tacks as set forth in claim 1, means for damping the movement of said gripper member comprising a piston-like extension on the gripper member, and a holding member having a cylindrical bore accommodating said piston-like extension to cushion the return movement of the gripper member, and a screw adjustable in said holder member to limit the return movement of the gripper member and thus determine the length of wire fed by said gripper member.

6. In a machine for the manufacture of wire tacks as set forth in claim 1, means for damping the movement of said gripper member comprising a piston-like extension on the gripper member, and a holding member having a cylindrical bore accommodating said piston-like extension and an air vent extending from the cylindrical bore to allow the gradual escapement of air from said bore under the action of the piston-like extension during the return movement of the gripper member.
